CLAIM

The ornamental design for a chair, as shown and described.

DESCRIPTION

FIG. 1 is a perspective view of my ornamental design;
FIG. 2 is a left elevation view of the ornamental design of FIG. 1;
FIG. 3 is a right elevation view of the ornamental design of FIG. 1;
FIG. 4 is a front plan view of the ornamental design of FIG. 1;
FIG. 5 is a rear plan view of the ornamental design of FIG. 1;
FIG. 6 is a top view of the ornamental design of FIG. 1;
and,
FIG. 7 is a bottom view of the ornamental design of FIG. 1;
and,
FIG. 8 is a perspective view of my ornamental design of FIG. 1 with broken lines showing cushions, which are shown for illustrative purposes only and form no part of the claimed design.

1 Claim, 8 Drawing Sheets
